FUEL INJECTOR FOR INTERNAL-
COMBUSTION ENGINESGeorge Wilfrid Acland Green, Staines, England,
assignor to Lagonda Limited, Staines, Middle-
sex, EnglandApplication September 24, 1943, Serial No. 503,708
In Great Britain September 25, 1942

1 Claim. (Cl. 137—153)

This invention relates to that type of fuel injector, for internal combustion engines, in which a spring-loaded needle valve movable axially of the injector body is adapted to be displaced periodically from its seat, afforded in a nozzle member situated at one end of the injector body, by fuel supplied under pressure to the interior of the injector in order to open a jet orifice or orifices through which fuel under pressure is then discharged.

A manufacturing difficulty inseparable from such an injector is the necessity of attaining a very high degree of concentricity between the seating faces on the needle valve and nozzle member respectively and the guiding surfaces of the needle valve and its guide without which correct functioning of the nozzle is impossible since fuel leakage past the valve seat will occur or the needle valve may even be deformed and jammed.

The present invention provides in a fuel injector of the type stated in the first paragraph above, the combination of a guide sleeve for the needle valve stem, said sleeve having diametral clearance in the injector body so as to be "self-centering" in the course of assembling the injector components, and means for rigidly retaining the sleeve in alignment with the valve seat on completion of assembly and throughout the operational movements of the valve.

With this arrangement the guide sleeve will be brought into exact alignment with the valve seat in the nozzle member to achieve the previously known effect of the valve being free to move to and from the seat without restraint from undesirable transverse forces, but in a manner which avoids the disadvantages of a freely floating guide, namely that disturbing influences may cause deviation of the needle valve when open and the consequent danger of the valve not again descending centrally to its seat without first striking the seat asymmetrically and then sliding to the fully closed position—an action which would cause uneven wear of the valve seat and imperfect sealing.

By way of non-limitative example two constructional forms of fuel injector embodying the invention are illustrated, in the accompanying drawing in which Figure 1 is a longitudinal sectional view of one form of fuel injector embodied in my invention; Fig. 2 is a fragmentary vertical sectional view of a modified view of fuel injector embodied in my invention and Fig. 3 is a transverse sectional view taken on line 3—3 of Fig. 1.

Referring first more particularly to Fig. 1, the fuel injector body 1 is bored longitudinally from

end to end, with a stepped-down portion 2 near its inner or lower end. The nozzle member 3 is a close diametral fit in this reduced bore and has a locating flange 4 which rests on the step, and through which radial fuel ports 5 are drilled. The needle valve 6 is axially slideable within the nozzle member 3 to control delivery of fuel to the jet orifice(s) formed in the outer end of the said member past a valve seat 7 within the nozzle member in the usual manner. This valve 6 has a shoulder 8 and, beyond the shoulder, a stem 9 which is a close sliding fit in a guide sleeve 10 disposed within the bore of the injector body 1. The guide sleeve 10 is given diametral clearance in the said bore as is clearly shown on the drawing.

A tubular distance piece 11 within the bore of the injector body 1 bears on the upper face of the guide sleeve 10 and is retained by the inner spigot portion 12 of a spring housing member 13 one end of which is screw-threaded into the upper or outer end of the injector body 1. The distance piece, which is a reasonably good fit in the bore of the injector body (although accuracy of this fit is not obligatory) has longitudinal grooves 14 in its outer periphery (four in the illustrated example) for the passage of fuel to the nozzle member 3 via the radial fuel ports 5 as shown more clearly in Fig. 3. Within the tubular distance piece 11 is a virtual extension 15 of the needle valve stem 9; it has a tapered lower portion 16 centering in an axial opening 17 in the upper end of the valve stem, and it carries, at its upper end, a seating washer 18 for the valve loading spring 19. The last mentioned is accommodated in the aforesaid housing member 13 and its other end engages another seating washer 20 which is guided by a plug 21 screwed into the cap 13a of the spring housing member 13.

On assembling the described components of the fuel injector the needle valve 6 is located in the nozzle member 3. The guide sleeve 10 for the valve stem 9 in its turn is located by the valve stem and as the spring housing 13 is screwed home, applying pressure to the loading spring 19, the point of the needle valve 6 is pressed by the pressure of spring 19 into the seating in the nozzle 3 and the guide sleeve 10 is gradually brought into line by the needle valve stem 9 and by the reactions at the faces of the nozzle member 3 and the distance piece 11 until it is finally clamped securely in true alignment with the valve seat 7 in the nozzle member as required to enable the valve to rise from and fall to its seat without restraint from undesirable transverse forces.

The fuel injector operates in the usual and well known manner which need not be described. Throughout the operation the initially aligned sleeve remains permanently clamped in position so that the needle valve cannot possibly deviate from its true axial position with the result that, in closing, there is no danger of it striking the valve seat off-centre, as could happen with a floating guide, and then sliding to the fully closed position, i. e., there is no danger of uneven wear of the valve seat and resultant leakage at the place of wear.

In the form illustrated by Fig. 2 the upper part 10a of the guide sleeve 10 for the needle valve stem 9 is externally stepped down to present a shoulder 22 and the lower part 15a of the hollow distance piece 15 is internally enlarged to pass over the reduced portion 10a of the guide sleeve and to bear on the shoulder 22 while standing clear of the top of the guide sleeve. The guide sleeve 10 has diametral clearance in the bore of the injector body while diametral clearance is also afforded between the upper part 10a of the sleeve and the lower part 15a of the distance

piece 15 so that, as before, the sleeve is free to align itself. In this arrangement the clamping force is applied to the guide sleeve at a locus below the top of the sleeve, namely, at the shoulder 22 presented by the reduced portion, the self-aligning action being thereby assisted in certain circumstances.

I claim:

In a fuel injecting valve for internal combustion engines, an injector body, a spring loaded needle valve spindle movable axially of the injector body, a valve seat member situated at one end of the injector body having an annular seat, a guide sleeve for the needle valve in said injector body, said guide sleeve having diametral clearance in the injector body so that said needle valve spindle may be accurately aligned with the valve seat during assembly of the injector components, and means for rigidly retaining the sleeve in that position in which the valve seat is aligned with said needle valve on completion of assembly thereof and throughout the operational movement of the valve.

GEORGE WILFRID ACLAND GREEN.
